MANUFACTURE OF COMBUSTIBLE GAS

Harry B. Pearson, New York, N. Y., assignor to
Allied Chemical & Dye Corporation, New York,
N. Y., a corporation of New York

Application September 2, 1949, Serial No. 113,765

9 Claims. (Cl. 48—214)

1

This invention relates to the manufacture of fuel gas from hydrocarbons and more particularly refers to a new and improved process and apparatus for converting normally liquid hydrocarbon oils and condensable hydrocarbon gases referred to in the industry as L. P. gas or liquid-petroleum gas which gases include propane, butane and pentane into a highly combustible homogeneous gas of a quality adapted to be principally used for heating.

In my cofiled United States application filed September 2, 1949, Serial No. 113,766, I have described an essentially unidirectional flow operation involving three primary zones to effect pyrolytic decomposition of hydrocarbon charging stock into combustible gas. The present invention is directed to a four-zone reverse directional flow system for the production of combustible gas from fluid hydrocarbon charging materials.

The discovery of increasing sources of natural gas in the Mid-west, South-central and Southwest parts of the United States together with improved technique in the fabrication of large size, high pressure steel pipe, and in the protective coatings to be applied thereto, has increased the distance from the producing wells that such gas may be economically transported. However, the cost of construction is of great magnitude, because of the vast distances involved which precludes the construction of parallel lines which might be utilized to avert cessation of delivery, in the case of pipe line failure, or to augment the normal capacity of the lines in the case of abnormal demand during extremely inclement weather conditions in the winter which is the peak demand period in most sections of the country for which this service is intended.

For many years the gas utilities in New England and the North Atlantic states have supplied their customers with heating and cooking gas either from coal gas retorts, by-product coke ovens or carburetted water gas plants, either separately, or mixed with one another, or with other types of manufactured gas such as blue water gas, or producer gas and L. P. gas. These sources of gas supply have generally been found inadequate in amount to meet peak loads and often too high in cost.

Attempts have been made to convert oil into the desired fuel gas without significant commercial success for reasons which may be better understood by a review of some of the requirements of the gas industry with respect to oil gas manufacture. Gas manufactured from oil whether the primary source of supply or the

supplemental means of insuring the consumers' fuel gas demands should desirably be of uniform quality with the proper combustion characteristics. An oil gas process should be elastic—i. e. capable of quickly, continuously producing gas from hydrocarbon oil and conversely shut down in a simple expeditious manner. The oil cracking apparatus should be flexible particularly in its ability to treat less costly fractions of petroleum oils such as low gravity gas oils or heavy residuums and also in its capability of changing the properties of the gas product within reasonable limits and its rate of production without seriously impairing the operation. Since price is a dominant factor controlling the sale of fuel gas over other competitive fuels all elements entering into the cost of the gas such as investment cost, value of charging stock, operating cost, maintenance and yield are of paramount importance to the manufacturer. In view of the high volume of gases consumed, small differentials in price per 1000 cu. ft. of heating gas which may appear insignificant, when multiplied by the total output of the gas in millions of cu. ft. assume substantial proportions in dollars. Furthermore, oil cracking machines should not only be simple and efficient in operation but also compact in design.

The quality of a heating gas is, of course, governed by the consumers' requirements. The greatest number of customers of gas burn gas in atmospheric gas burners fixed in the sense of having orifices of a definite size and air shutters open to a predetermined extent which cannot conveniently be changed thereby imposing on the gas producer the necessity for maintaining a uniform quality of gas. Other important considerations in the efficient operation of atmospheric burners are the properties of the gas, particularly the calorific value and density of the gas. Desirably a gas should have a B. t. u. per cu. ft. in excess of about 800 and generally above 950 and a specific gravity (air=1) between about 0.6 and 0.8, preferably about 0.68, an oil gas having these characteristics being hereinafter designated as "high B. t. u. low gravity gas." The density of a gas is influenced to a large degree by its content of hydrogen and illuminants, i. e. hydrocarbons of higher molecular weight. Gases containing too large a volume of hydrogen tend to "flash-back" and gases having too large a percentage of illuminants give an elongated flame. To my knowledge none of the prior art oil cracking devices has succeeded in commercially producing high B. t. u. low gravity gas.

One object of the present invention is to provide an efficient process for converting oil into gas of greater uniformity with desirable combustion characteristics than has hitherto been attained.

Another object of this invention is to provide a gas producing process utilizing low grade petroleum oils as raw charging stock with the elimination of by-product residual carbonaceous material or free carbon and with improved thermal operation.

A further object of the invention is to provide an oil gas apparatus simple in construction, compact in design, and durable, certain and efficient in operation.

A still further object of this invention is to provide an improved process and apparatus for decomposing hydrocarbon oils into gas which is economical, elastic and flexible in operation.

Further objects and advantages will be apparent from the description and accompanying drawing.

Apparatus for carrying out the conversion of oil into gas in accordance with the present invention involves a novel combination and arrangement of elements including two vertical refractory lined duplicate vessels connected at their tops by a gas channel, each vessel constructed to provide an empty chamber above another chamber at least partially filled with checkerbrick or refractory material with voids therebetween to permit the passage of gas therethrough and divided therefrom by a refractory circular orifice, two vertical refractory lined riser pipes extending upwardly to a height above the vessels with each riser pipe connected to the base of a refractory filled chamber, a stack valve fitted to the top of each riser pipe, conduits leading from the top of each riser pipe connected to a three-way valve for reversal of flow in the apparatus and for the release of make gas, an inlet for the introduction of primary air into each riser pipe, a steam conduit leading into each riser pipe, a gas inlet for the introduction of hydrocarbon carrier gas into the base of each refractory filled chamber, secondary air inlets leading into each empty chamber, a downwardly directed spray nozzle near the top of each empty chamber for the dispersion of make oil and a heat oil inlet disposed near the bottom of each empty chamber.

The operation of my process involves passing air upwardly through a first zone at least partially filled with heated refractory material with voids therebetween to permit the passage of air therethrough thereby preheating the air, introducing the preheated air upwardly into a second empty zone in direct contact with a combustible material which burns in the presence of the preheated air thus imparting heat to the walls of the second zone, passing the combustion gases resulting from the reaction of the combustible material and air downwardly through a third empty zone thereby transmitting heat to the walls of the third zone, thence passing the combustion gases downwardly through a fourth zone at least partially filled with refractory material with voids therebetween to permit the passage of gas therethrough thereby transferring heat from the combustion gases to the refractory material, and discharging the combustion gas from the fourth zone; passing a hydrocarbon carrier gas and steam upwardly through the first zone, introducing the mixture of steam and hydrocarbon

carrier gas into the second zone and simultaneously injecting hydrocarbon charging stock into the second zone countercurrent to the upward flow of steam and hydrocarbon carrier gas maintained at a velocity sufficiently high to prevent passage of carbonaceous material downwardly out of the second zone, withdrawing gaseous constituents substantially free from solid and liquid carbonaceous materials from the top of the second zone, directing them downwardly through the third and fourth zones thereby fixing the gases, and discharging the gaseous constituents from the fourth zone; a reverse flow of air as described above; and a reverse flow of steam and hydrocarbon carrier gas as described above.

A preferred method for conducting a complete cycle of operation comprises, (a) a blast period wherein air passes downwardly through a riser pipe connected to the base of a first vessel, upwardly through checkerbrick contained in the bottom chamber of the first vessel thereby preheating the air, thence discharging the preheated air from the top of the bottom chamber containing checkerbrick through an orifice into an empty chamber disposed above the bottom chamber wherein secondary air is admitted and heating oil is introduced, which latter burns thus imparting heat to the walls of the first empty chamber, then directing the combustion gases through a gas channel to the top of a second empty chamber in a second vessel, downwardly through the second empty chamber thereby transferring heat from the combustion gases to its walls and burning any carbonaceous deposits thereon by means of excess secondary air, continuing the passage of combustion gases from the bottom of the second empty chamber through an orifice downwardly through a second bottom chamber containing checkerbrick disposed beneath the second empty chamber thereby heating the checkerbrick therein, and then discharging the combustion gases to the atmosphere through a second riser pipe leading from the base of the second bottom chamber; (b) a purge period for the evacuation of combustion gases contained in the system wherein steam introduced into the first riser pipe passes upwardly through the first vessel, downwardly through the second vessel, and discharges to the atmosphere through the second riser pipe; (c) a make period wherein steam and a hydrocarbon carrier gas introduced into the first riser pipe pass upwardly through the checkerbrick of the first bottom chamber, thence discharging through an orifice upwardly into the first empty chamber countercurrent to the downwardly sprayed make oil, maintaining the velocity of the mixture of steam and hydrocarbon carrier gas sufficiently high to prevent passage of oil vapors and carbon to the chamber beneath the orifice, withdrawing gaseous constituents substantially free of solid carbonaceous material and liquid oil from the top of the first empty chamber through a gas channel into the top of a second empty chamber, then passing the gaseous constituents downwardly through the second empty chamber, the second orifice and the second bottom chamber thereby fixing the gas, and discharging the gaseous constituents from the bottom of the second bottom chamber through the second riser pipe; (d) a second purge period for the displacement of gaseous constituents in the system whereby steam introduced into the first riser pipe passes

upwardly through the first vessel, downwardly through the second vessel, and discharges through the second riser pipe; (e) a reverse blast period as described in (a) above; (f) a reverse purge period as described in (b) above; (g) a reverse make period as described in (c) above; (h) a reverse purge period as described in (d) above.

While I do not wish to predicate my invention on any particular theory or mechanism of reaction the following explanation may aid in a better understanding of the process and its attendant advantages over the prior art.

The formation of carbon and carbonaceous materials are an inevitable by-product resulting from the pyrolytic decomposition of hydrocarbons, particularly residual oils, into gas. These carbonaceous deposits have a detrimental effect on oil-gas cracking operations in several respects, among which are loss in yield of fuel gas product, plugging of apparatus, decreased efficiency of operation and rapid deterioration of apparatus. In the operation in accordance with the present invention the bulk of the carbonaceous material resulting from the conversion of the oil into gas is confined within an empty chamber out of the path of the checkerbrick section in the apparatus and only oil vapors and gases substantially free from solid carbonaceous materials and liquid oils are subjected to a fixing operation in the checkerbrick section. This I accomplish by first heating the empty chamber to a peak cracking temperature of the system and then injecting hydrocarbon oil into the heated empty chamber countercurrent to an upward flow of a mixture of steam and hydrocarbon carrier gas introduced into the bottom of the empty chamber at a velocity high enough to prevent the oil and carbonaceous materials from flowing down through the chamber. The combination of upwardly flowing steam and hydrocarbon gas and peak temperature in the empty chamber causes vaporization and cracking of the liquid oil with concomitant production of carbon and carbonaceous material which deposit on the walls of the empty chamber leaving effluent vapors and gas substantially free from solid carbonaceous material and liquid oil for further conversion, i. e. fixing, in a separate zone. Confining the bulk of the carbonaceous material to the walls of an empty chamber is beneficial in that the flow of materials through the apparatus is not materially impeded, thus maintaining high throughput as well as reducing shut-downs for cleaning. Furthermore, avoidance of material deposition of carbonaceous material on the checkerbrick eliminates rapid deterioration of the brickwork which normally requires frequent replacement, due, it is believed, to thermal shock resulting from direct impingement of the carbon on the checkerbrick and the burning of the carbon from the checkerbrick causing localized hot spots.

The addition of a hydrocarbon carrier gas to the steam during the make period has manifold advantages. It supplements the steam as a propelling agent for carrying the oil vapors through the apparatus. It aids in preventing oil and carbonaceous material from dropping down through the bottom of the empty chamber. It facilitates vaporization of the oil and better distribution of the oil vapors undergoing further cracking, and in addition permits the use of a smaller amount of steam during the make period, the advantage of which is reflected in lower cost of steam and more intensive cracking conditions

with increased capacity. The replacement of a portion of the steam with a hydrocarbon carrier gas during the make period has the effect of maintaining a higher temperature in the cracking zone for the reason that the heat requirements for steam including its endothermic heat of reaction under the conditions of operation are appreciably higher than the heat requirements of the hydrocarbon carrier gas, consequently the steam extracts a greater amount of heat from the equipment and lowers its temperature to a greater degree than an equivalent volume of carrier gas. Since cracking is a function of temperature, pyrolytic conversion of the oil into gas proceeds at a much more rapid rate when hydrocarbon gas replaces steam as the propelling medium. Of course the use of some steam is desirable for the purpose of converting the carbonaceous deposits into blue gas. The use of recycle make gas as the hydrocarbon carrier gas has the further important advantage of degrading the higher molecular weight hydrocarbon gases thus reducing the percentage of illuminants in the final gas and lowering its specific gravity.

One of the difficulties encountered in the prior art processes is the variable temperature in the cracking zone, particularly the checkerbrick section, developing a sharp temperature gradient with localized hot spots therein. As a result, portions of the oil are overcracked with the deposition of excess carbon and other portions of the oil are undercracked with incomplete utilization of the oil. I have discovered that more favorable temperature conditions in the cracking zone may be attained by blasting upwardly through an empty reaction zone to a peak gas making temperature and then passing combustion gases downwardly through another empty zone and a zone filled with refractories. The downward flow of gases through the empty reaction zone and checkerbrick section of the fixing zone gives a relatively even downward temperature gradient following the path of combustion gases and a more uniform heat distribution throughout the checkerbrick section. The introduction of a hydrocarbon carrier gas during the make period has the cumulative effect of better distribution of the oil thereby also minimizing overcracking and undercracking.

The particular arrangement of apparatus and method of operation as taught herein results in more effective utilization of the equipment for carrying out cracking in that the greater part of the equipment is maintained under cracking conditions and utilized for effecting the conversion of oil into gas, the remaining portion of the equipment serving to conserve heat by preheating the steam and air entering the system. It will be observed that these efficient cracking conditions are maintained regardless of the direction of flow of fluids in the system.

The introduction of a hydrocarbon carrier gas during the make period of the operation provides a simple convenient method of imparting flexibility to the operation merely by changing the amount of hydrocarbon carrier gas.

As will be evident from the preceding discussion the various operating principles incorporated in my process not only have individual beneficial effects but also cooperate with one another to produce cumulative advantages.

The accompanying drawing is a diagrammatic flow sheet illustrating the apparatus and process of the present invention.

Referring to the drawing, the apparatus may be divided for the purpose of ready reference into No. 1 set and its counterpart No. 2 set, both sets being joined by a crossover at their top as well as connecting pipework. Vessel 1 of No. 1 set is preferably constructed of a metal shell 2 lined with firebrick, tiles or other suitable refractory materials 3 which refractory lining absorbs heat and also protects the metal shell 2 which surrounds it from the direct impact of hot gases. As an added protective measure, insulation 10 may be interposed between shell 2 and refractory lining 3. Vessel 1 is divided into two sections, an empty upper reaction chamber 4 and a lower pre-heating or fixing chamber 5 filled with a refractory material 6 wherein will be retained and stored up surplus heat and which will give up heat. Dividing reaction chamber 4 and fixing chamber 5 is a circular orifice 7 which has the function of effecting thorough mixing of the gases and also imparting a high velocity to the gas entering the bottom of chamber 4. A refractory lined conduit 8 connects the bottom of vessel 1 with the bottom of refractory lined riser pipe 9 which extends upwardly to a height suitable to carry the blast gases above other equipment and to provide draught when the set is shut down. A stack valve 11 is fitted to the top of riser pipe 9 and disposed above it is stack 12. Make gas discharges from the top of riser pipe 9 through line 13 connected to a conventional three-way reversing valve 14. Primary air introduced for example by a blower, not shown in the drawing, enters conduit 15 passing through line 16, valve 17 and line 18 into riser pipe 9 or, if desired, the primary air may be blown directly into riser pipe 9. Steam may be introduced into riser pipe 9 through line 18 and valve 19. Hydrocarbon carrier gas from an external source joins the flow of steam entering through line 65, valve 20 and entrance 21, preferably disposed at the bottom of riser pipe 9.

In the preferred method of operation recycle make gas is returned as the carrier agent to the bottom of preheating chamber 5 through line 66, valve 67, exhauster 68, valve 20 and inlet 21. Make oil is fed through lines 22, 23, valve 24 and sprayed downwardly by means of nozzle 25, of conventional design, counter-current to the upward flow of gases in reaction chamber 4. Heat oil passes through line 26, 27, valve 28 into reaction chamber 4 through nozzle 29. Secondary air supplied by a suitable blower, not shown in the drawing, flows through conduit 31, 32, valve 33 into reaction chamber 4. Gases enter or leave the top of vessel 1 through refractory lined crossover or gas channel 34.

Although not a preferred method of operation, the introduction of a carrier gas may be dispensed with entirely and steam in the absence of carrier gas employed as the propelling medium during the make period. In some instances in the operation of the process, the introduction of carrier gas may be omitted during certain of the make periods or during part of the make periods. For example, during the first part of a make period the quantity of make gas produced may be so small as to make it difficult to recycle make gas at the initial stage of the make period and therefore the return of make gas may desirably be delayed for, by way of illustration, the first 30 seconds. Also, due to special circumstances an operator may wish to limit the degradation of make gas normally accomplished by recycling in which

event no make gas would be recycled or make gas returned only during a part of the make time.

No. 2 set and No. 1 set are substantially duplicates, the corresponding elements of set No. 2 bearing the following numerals: Vessel 35, metal shell 36, refractory lining 37, reaction chamber 38, fixing chamber 39, checkerbrick 41, orifice 42, riser pipe 43, connecting conduit 44, stack valve 45, stack 46, steam inlet and valve 47 and 48, respectively, hydrocarbon carrier gas inlet and valve 49 and 50, hydrocarbon carrier gas conduit from an external source 69, recycle line, valve, exhauster 71, 72 and 73, respectively, primary air inlet and valve 52 and 53, respectively, secondary air inlet and valve 54 and 55, respectively, make oil line, valve and nozzle 56, 57 and 58, respectively, heat oil line, valve and nozzle 59, 61 and 62, respectively.

A complete cycle of operation in accordance with the present invention may be divided into four primary periods—a blast period, a make gas period, a reverse blast period and a reverse make period with purges between the primary periods.

Preparatory to conducting the blast period, stack valve 11 is closed, stack valve 45 is open and reversing valve 14 is set against No. 1 set. Primary air is admitted through lines 15, 16, valve 17, line 18 into the top of riser pipe 9 passing downwardly therethrough and through conduit 8 thereby partially preheating the air by its contact with the refractory lining before entering the bottom of chamber 5. The partially preheated air passes upwardly through checkerbrick 6 thereby becoming heated to a higher temperature by refractory 6 and also burns any slight amount of carbon which may be deposited thereon. The highly preheated air flows through orifice 7 into empty chamber 4 wherein secondary air enters by way of lines 31, 32 and valve 33. Heat oil pumped through lines 26, 27 and valve 28 discharges through nozzle 29 into the atmosphere of air whereupon the oil ignites, generating heat which is imparted to the walls of chamber 4. The quantity of air supplied should desirably be greater than that required for complete combustion of the heat oil, thereby providing an excess of air for burning any carbonaceous deposits from the walls of chamber 4 made during a previous make period. Combustion gases together with highly heated secondary air pass through crossover 34, downwardly through empty chamber 38 heating its walls and burning carbon thereon. Thus, carbonaceous deposits unconverted into blue gas during the make period are utilized for heating the reaction chambers, effecting a saving in heat oil consumed and in some instances eliminating the need for heat oil. The resultant combustion gases pass through orifice 42, downwardly through fixing chamber 39, heating checkerbrick 41 and out through riser pipe 43. As a result of blasting, the refractories in reaction chambers 4 and 38 and fixing chamber 39 attain suitable gas-making temperatures, preferably between 1500° F. and 2200° F., with a relatively even downward temperature gradient following the path of the combustion gases and a more uniform heat distribution throughout the checkerbrick section 41. I attribute the more uniform temperature conditions due to the particular upward and downward passage of the hot combustion gases in the chambers. Another important factor in my procedure of blasting is the maintenance of the highest temperatures in empty zones to effect complete vaporization of

the oil and deposition of carbon inherent in the pyrolytic decomposition of oil on the walls of the empty chambers prior to passage of the gaseous constituents through the fixing chamber thereby avoiding clogging or plugging of the checkerbrick section. I have also discovered that by maintaining the highest temperatures in the empty chambers 4 and 38 with lower more uniform temperatures in checkerbrick sections 6 and 41 I materially reduce spalling of the checkerbrick sections commonly caused by intense heat, sharp temperature differentials therein and flame temperatures caused by burning of heavy deposits of carbon thereon.

In order to avoid diluting the product gas with inert combustion gases contained in the cavity of the system following the blast period, I prefer to purge the system preliminary to carrying out the make period. The combustion gases may be conveniently blown out by blowing with steam entering the top of riser pipe 9 through line 18 and valve 19 and discharging the gases from the top of riser pipe 43. At the end of the blast and purge periods valves 28, 17, 33 and 45 are closed.

It is important to carry out the make period, that is the gasification of the oil following the blast period, in the same directional flow as the blast period. At the start of the make period on No. 1 set, steam valve 19 is opened, make oil valve 24 is opened and exhauster 13 put in operation for the return of recycle gas through inlet at 21. Steam introduced at the top of the riser pipe 9 passes downwardly through the same and with recycle gas entering 21 moves upwardly through checkerbrick section 6 of chamber 5 where it is highly superheated and expanded. The mixture of superheated steam and recycle gas discharges through orifice 7 at a high velocity and meets a downward hollow cone of sprayed oil ejected through nozzle 25. A linear velocity of the mixture of steam and gas of about 50 feet per second will for most conditions of operation be found satisfactory. Vaporization of the oil occurs almost instantaneously in the empty space of reaction chamber 4 and substantially all the carbon liberated as a result of the vaporization and cracking of the oil therein will adhere to the internal surface of empty chamber 4. Upon reaching incandescence this carbon will react with the steam to form blue gas. Carbon remaining on the walls of chamber 4 will be converted to heat on a subsequent blast run. The mixture of gases discharges from the top of chamber 4, through crossover 34 into empty chamber 38, also at a high temperature due to the previous blasting operation, wherein decomposition of the oil vapor molecules continues with further deposition of carbon on the walls of empty chamber 38 (minor in amount in comparison with the carbon deposited in chamber 4) and further production of blue gas during the downward passage of the gas and steam in vessel 35. By the time the gases pass through orifice 42 cracking of the oil into gas has in large measure been accomplished and generally more than 90% of the total carbon resulting from the conversion of the oil has been deposited on the walls of empty chambers 4 and 38 out of the path of checkerbrick 41. The gases are fixed by their downward passage through checkerbrick 41 which is at a temperature high enough to finish the decomposition of the oil vapors and to convert such oil vapors into an oil gas.

Recycling of the make gas desirably in an

amount between 10 and 35% of the volume of make gas into inlet 21 may be accomplished in various manners, as for example by the use of a steam injector to withdraw a portion of the make gas from the bottom of vessel 35 or as an alternative to install a gas exhauster to withdraw make gas from the foul main and introduce the make gas with steam at the top of riser pipe 18. In some instances the return of a portion of make gas from crossover 34 to riser pipe 9 or the bottom of fixing chamber 1 may be found advantageous. It is not essential to admix the hydrocarbon carrier gas with the steam prior to passage through refractories 6 and therefore the carrier gas may be commingled with the steam near the bottom entrance of reaction chamber 4. A normally gaseous hydrocarbon such as methane, ethane, propane or mixtures thereof may be employed as the hydrocarbon carrier gas from an external source.

10 The combination of hydrocarbon carrier gas and my method of blasting and making have the cumulative effect of reducing the amount of carbon deposited which permits the use of smaller quantities of steam which in turn results in a higher calorific gas since the greater the amount of steam the lower the B. t. u. content of the gas.

15 The make gases leaving the bottom of vessel 35 pass through conduit 44 up through riser pipe 43 and thence discharge through conduit 51 and valve 14 to conventional washbox and foul gas main, not shown in the drawing.

20 The reverse blast period and make period are similar to the make period and blast period previously described and need no further elaboration other than the statement that the flow of fluids is downwardly through riser pipe 43, upwardly through vessel 35, downwardly through vessel 4 and upwardly and out through riser pipe 9.

25 The time for individual blast and make periods will vary dependent upon the nature of the charging oil, operating conditions and quality of gas desired. Blast and make periods of from 3-10 minutes duration will ordinarily be found satisfactory. High superatmospheric or subatmospheric pressures are unnecessary since the operation of my process may be carried out efficiently at substantially atmospheric pressure.

30 In order to avoid an explosion hazard, the system should be purged of combustible gas prior to the introduction of air in the succeeding blast period. Purging may be accomplished by passing steam in through line 47 and out through the top of riser pipe 9.

35 In the practice of my process a wide variety of charging stocks ranging from L. P. gas to heavy liquid hydrocarbon oils may be treated. A particular advantage of the present invention resides in the provision of an apparatus and process for the conversion of low grade hydrocarbon oils such as heavy cracked residuums having a Conradson carbon number in excess of 10 into high gravity low B. t. u. gas without choking up the apparatus with carbon and, indeed, with the total elimination of carbonaceous material as by-product.

40 Although certain preferred embodiments of the invention have been disclosed for purpose of illustration it will be evident that various changes and modifications may be made therein without departing from the scope and spirit of the invention.

45 I claim:

50 1. A process for the production of combustible gases which comprises, (a) a blast period where-

in air passes downwardly through a previously heated riser pipe thereby effecting partial heating of the air, upwardly through the interstices of heated refractories contained in a first zone thereby further heating the air, passing the pre-heated air into a second empty zone wherein secondary air and heating fluid are introduced, which latter burns to impart heat to the walls of the empty zone, passing the combustion gases resulting from the reaction of the combustible fluid and air together with excess air downwardly through a third empty zone thereby transferring heat from the combustion gases to its walls and burning any carbonaceous deposits thereon by means of the excess air, continuing the passage of combustion gases downwardly through the interstices of refractories contained in a fourth zone thereby heating the refractories therein, and then discharging the combustion gases to the atmosphere through a second riser pipe leading from the base of the fourth zone; (b) a purge period for the evacuation of combustion gases contained in the system wherein steam introduced into the first riser pipe passes upwardly through the first and second zones, downwardly through the third and fourth zones, and discharges to the atmosphere through the second riser pipe; (c) a make period wherein steam introduced into the first riser pipe is admixed with a hydrocarbon carrier gas and the mixture passes upwardly through the refractories in the first zone, thence upwardly into the second empty zone countercurrent to downwardly injected hydrocarbon charging stock, maintaining the velocity of the mixture of steam and hydrocarbon carrier gas sufficiently high to prevent passage of carbonaceous material downwardly out of the second zone, withdrawing gaseous constituents substantially free of solid and liquid carbonaceous material from the top of the second empty zone, passing the gaseous constituents downwardly through the third and fourth zones thereby fixing the gas, and discharging the gaseous constituents from the bottom of the fourth zone through the second riser pipe; (d) a second purge period for the displacement of gaseous constituents in the system wherein steam introduced into the first riser pipe passes upwardly through the first and second zones, downwardly through the third and fourth zones, and discharges through the second riser pipe; (e) a reverse blast period as described in (a) above; (f) a reverse purge period as described in (b) above; (g) a reverse make period as described in (c) above and (h) a reverse purge period as described in (d) above.

2. A process for the production of combustible gases which comprises, (a) a blast period wherein air passes downwardly through a previously heated riser pipe thereby effecting partial heating of the air, upwardly through the interstices of heated refractories contained in a first zone thereby further heating the air, passing the pre-heated air into a second empty zone wherein secondary air and heat oil are introduced, which latter burns to impart heat to the walls of the empty zone, passing the combustion gases resulting from the reaction of the heat oil and air together with excess air downwardly through a third empty zone thereby transferring heat from the combustion gases to its walls and burning any carbonaceous deposits thereon by means of the excess air, continuing the passage of combustion gases downwardly through the interstices of refractories contained in a fourth zone thereby

heating the refractories therein, and then discharging the combustion gases to the atmosphere through a second riser pipe leading from the base of the fourth zone; (b) a purge period for the evacuation of combustion gases contained in the system wherein steam introduced into the first riser pipe passes upwardly through the first and second zones and downwardly through the third and fourth zones, and discharges to the atmosphere through the second riser pipe; (c) a make period wherein steam introduced into the first riser pipe is admixed with a hydrocarbon carrier gas and the mixture passes upwardly through the refractories in the first zone, thence upwardly into the second empty zone countercurrent to downwardly injected heavy residual oil, maintaining the velocity of the mixture of steam and hydrocarbon carrier gas sufficiently high to prevent passage of carbonaceous material downwardly out of the second zone, withdrawing gaseous constituents substantially free of solid and liquid carbonaceous material from the top of the second empty zone, passing the gaseous constituents downwardly through the third and fourth zones thereby fixing the gas, recycling a portion of the gaseous constituents to the first zone as the hydrocarbon carrier gas, and discharging gaseous constituents from the bottom of the fourth zone through the second riser pipe; (d) a second purge period for the displacement of gaseous constituents in the system wherein steam introduced into the first riser pipe passes upwardly through the first and second zone, downwardly through the third and fourth zones, and discharges through the second riser pipe; (e) a reverse blast period as described in (a) above; (f) a reverse purge period as described in (b) above; (g) a reverse make period as described in (c) above; and (h) a reverse purge period as described in (d) above.

3. Apparatus adapted for converting hydrocarbons into combustible gas which comprises a combination of a first chamber at least partially filled with refractory mass having voids therein to permit the passage of gas therethrough, a second empty refractory lined chamber, a restricted passageway connecting the top of the first chamber with the bottom of the second chamber, a third empty refractory lined chamber, a gas channel connecting the tops of the second and third empty chambers, a fourth chamber at least partially filled with a refractory mass having voids therein to permit the passage of gas therethrough, a restricted passageway connecting the bottom of the third chamber with the top of the fourth chamber, two riser pipes extending upwardly to a height above the chambers with one riser pipe connected at its base to the bottom of the first chamber and the other riser pipe connected at its base to the bottom of the fourth chamber, inlets for the introduction of primary air and hydrocarbon carrier gas into the bottoms of the first and fourth chambers, inlets for the introduction of secondary air and a combustible fluid into the second and third chambers, and spray nozzles near the top of the second and third chambers for the injection of hydrocarbon charging stock.

4. Apparatus for converting hydrocarbon oil into oil gas which comprises two vertical refractory lined vessels connected at their tops by a gas channel, each vessel constructed to provide an empty chamber above a checkerbrick section, two vertical riser pipes extending upwardly to a height above the vessels with each riser pipe con-

ected to the base of a vessel, inlets for the introduction of primary air and steam into each riser pipe, connecting conduits for the passage of recycle gas into the base of each vessel, inlets for the introduction of secondary air and heat oil into the empty chambers above the checker-brick sections, and spray nozzles near the top of each empty chamber for the downward injection of hydrocarbon oil.

5. Apparatus for converting hydrocarbon oil into oil gas which comprises two vertical refractory lined duplicate vessels connected at their tops by a gas channel, each vessel constructed to provide an empty chamber above another chamber at least partially filled with refractory material with voids therebetween to permit passage of gas therethrough and divided therefrom by a refractory orifice, two vertical refractory lined riser pipes extending upwardly to a height above the vessels with each riser pipe connected to the base of each vessel, a stack valve fitted to the top of each riser pipe, conduits leading from the top of each riser pipe connected to a three-way valve for reversal of flow in the apparatus and for release of make gas, inlets for the introduction of primary air and steam into each riser pipe, conduits for the return of recycle make gas to the bottom of each vessel, inlets for the introduction of secondary air and heat oil into each empty chamber, and downwardly directed spray nozzles disposed near the top of each empty chamber for the injection of hydrocarbon oil.

6. A process for the production of combustible gas which comprises passing air upwardly through the interstices of heated refractories contained in a first zone thereby preheating the air, passing the preheated air into a second empty zone wherein heating fluid is introduced, which latter burns to impart heat to the walls of the empty zone, passing the resultant combustion gases downwardly through a third empty zone thereby transferring heat from the combustion gases to its walls, continuing the passage of combustion gases downwardly through the interstices of refractories contained in a fourth zone thereby heating the refractories therein, and then discharging the combustion gases from the fourth zone; passing steam upwardly through the refractories of the first zone thereby heating and expanding the steam, passing the expanded steam upwardly into the second empty zone countercurrent to downwardly injected hydrocarbon charging stock, maintaining the velocity of the steam sufficiently high to substantially prevent passage of carbonaceous material downwardly out of the second zone, withdrawing gaseous constituents substantially free of solid and liquid carbonaceous material from the top of the second empty zone, passing the gaseous constituents downwardly through the third and fourth zones thereby fixing the gas, and discharging the gaseous constituents from the fourth zone; passing air upwardly through the interstices of heated refractories contained in the fourth zone thereby preheating the air, passing the preheated air into the third empty zone wherein heating fluid is introduced, which latter burns to impart heat to the walls of the third empty zone, passing the resultant combustion gases downwardly through the second empty zone thereby transferring heat from the combustion gases to its walls, continuing the passage of combustion gases downwardly through the interstices of refractories contained in the first zone thereby heating the refractories therein, and then discharging the combustion gases from the first zone; passing steam upwardly through the refractories of the fourth zone thereby heating and expanding the steam, introducing a hydrocarbon carrier gas into the third zone, passing the mixture of expanded steam and hydrocarbon carrier gas upwardly through the third empty zone countercurrent to downwardly injected hydrocarbon charging stock, maintaining the velocity of the steam and gas mixture sufficiently high to prevent passage of carbonaceous material downwardly out of the third zone, with-

fractories therein, and then discharging the combustion gases from the first zone; passing steam upwardly through the refractories of the fourth zone thereby heating and expanding the steam, passing the expanded steam upwardly into the third empty zone countercurrent to downwardly injected hydrocarbon charging stock, maintaining the velocity of the steam sufficiently high to substantially prevent passage of carbonaceous material downwardly out of the third empty zone, withdrawing gaseous constituents substantially free of solid and liquid carbonaceous material from the top of the third empty zone, passing the gaseous constituents downwardly through the second and first zones thereby fixing the gas, and discharging the gaseous constituents from the first zone.

7. A process for the production of combustible gas which comprises passing air upwardly through the interstices of heated refractories contained in a first zone thereby preheating the air, passing the preheated air into a second empty zone wherein heating fluid is introduced, which latter burns to impart heat to the walls of the empty zone, passing the resultant combustion gases downwardly through a third empty zone thereby transferring heat from the combustion gases to its walls, continuing the passage of combustion gases downwardly through the interstices of refractories contained in a fourth zone thereby heating the refractories therein, and then discharging the combustion gases from the fourth zone; passing steam upwardly through refractories of the first zone thereby heating and expanding the steam, introducing a hydrocarbon carrier gas into the second zone, passing the mixture of expanded steam and hydrocarbon carrier gas upwardly through the second empty zone countercurrent to downwardly injected hydrocarbon charging stock, maintaining the velocity of the steam and gas mixture sufficiently high to prevent passage of carbonaceous material downwardly within the second zone, withdrawing gaseous constituents substantially free of solid and liquid carbonaceous material from the top of the second empty zone, passing the gaseous constituents downwardly through the third and fourth zones thereby fixing the gas, and discharging the gaseous constituents from the fourth zone; passing air upwardly through the interstices of heated refractories contained in the fourth zone thereby preheating the air, passing the preheated air into the third empty zone wherein heating fluid is introduced, which latter burns to impart heat to the walls of the third empty zone, passing the resultant combustion gases downwardly through the second empty zone thereby transferring heat from the combustion gases to its walls, continuing the passage of combustion gases downwardly through the interstices of refractories contained in the first zone thereby heating the refractories therein, and then discharging the combustion gases from the first zone; passing steam upwardly through the refractories of the fourth zone thereby heating and expanding the steam, introducing a hydrocarbon carrier gas into the third zone, passing the mixture of expanded steam and hydrocarbon carrier gas upwardly through the third empty zone countercurrent to downwardly injected hydrocarbon charging stock, maintaining the velocity of the steam and gas mixture sufficiently high to prevent passage of carbonaceous material downwardly out of the third zone, with-

drawing gaseous constituents substantially free of solid and liquid carbonaceous material from the top of the third empty zone, passing the gaseous constituents downwardly through the second and first zones thereby fixing the gas, 5 and discharging the gaseous constituents from the first zone.

8. A process for the production of combustible gas which comprises passing air upwardly through the interstices of heated refractories contained in a first zone thereby preheating the air, passing the preheated air into a second empty zone wherein heating fluid is introduced, which latter burns to impart heat to the walls of the empty zone, passing the resultant combustion gases downwardly through a third empty zone thereby transferring heat from the combustion gases to its walls, continuing the passage of combustion gases downwardly through the interstices of refractories contained in a fourth zone thereby heating the refractories therein, and then discharging the combustion gases from the fourth zone; passing steam upwardly through the refractories of the first zone thereby heating and expanding the steam, introducing into the second zone a portion of the effluent gaseous reaction products formed in the second zone, passing the mixture of expanded steam and said effluent gaseous reaction products upwardly through the second empty zone countercurrent to downwardly injected hydrocarbon charging stock, maintaining the velocity of the steam and gas mixture sufficiently high to prevent passage of carbonaceous material downwardly out of the second zone, withdrawing gaseous constituents substantially free of solid and liquid carbonaceous material from the top of the second empty zone, passing the gaseous constituents downwardly through the third and fourth zones thereby fixing the gas, and discharging the gaseous constituents from the fourth zone; passing air upwardly through the interstices of heated refractories contained in the fourth zone thereby preheating the air, passing preheated air into the third empty zone wherein heating fluid is introduced, which latter burns to impart heat to the walls of the third empty zone, passing the resultant combustion gases downwardly through the second empty zone thereby transferring heat from the combustion gases to its walls, continuing the passage of combustion gases downwardly through the interstices of refractories contained in the first zone thereby heating the refractories therein, and then discharging the combustion gases from the first zone; passing steam upwardly through the refractories in the fourth zone thereby heating and expanding the steam, introducing into the third zone a portion of the

effluent gaseous reaction products formed in the third zone, passing the mixture of expanded steam and said effluent gaseous reaction products upwardly through the third empty zone countercurrent to downwardly injected hydrocarbon charging stock, maintaining the velocity of the steam and gas mixture sufficiently high to prevent passage of carbonaceous material downwardly out of the third zone, withdrawing gaseous constituents substantially free of solid and liquid carbonaceous material from the top of the third empty zone, passing the gaseous constituents downwardly through the second and first zones thereby fixing the gas, and discharging the gaseous constituents from the first zone.

9. Apparatus adapted for converting hydrocarbons into combustible gas which comprises a combination of a first chamber at least partially filled with refractory mass having voids therein to permit the passage of gas therethrough, a second empty refractory lined chamber, a restricted passageway connecting the top of the first chamber with the bottom of the second chamber, a third empty refractory lined chamber, a gas channel connecting the tops of the second and third empty chambers, a fourth chamber at least partially filled with a refractory mass having voids therein to permit the passage of gas therethrough, a restricted passageway connecting the bottom of the third chamber with the top of the fourth chamber, two riser pipes extending upwardly to a height above the chambers with one riser pipe connected at its base to the bottom of the first chamber and the other riser pipe connected at its base to the bottom of the fourth chamber, inlets for the introduction of air into the first and fourth chambers, inlets for the introduction of a combustible fluid into the second and third chambers, and spray nozzles near the top of the second and third chambers for the injection of hydrocarbon charging stock.
